DESIGN FOR A CLOCK OR SIMILAR ARTICLE

Abraham K. Simons, Chicago, Ill.

Application May 17, 1946, Serial No. 129,783

Term of patent 7 years

(Cl. D42—7)

To all whom it may concern:

Be it known that I, Abraham K. Simons, a citizen of the United States, residing at Chicago, in the county of Cook and State of Illinois, have invented a new, original, and ornamental Design for a Clock or Similar Article, of which the following is a specification, reference being had to the accompanying drawing, forming a part thereof.

Figure 1 is a front elevational view of the clock or similar article, embodying my new design; and Fig. 2 is a side elevational view thereof.

I claim:

The ornamental design for a clock or similar article, substantially as shown.

ABRAHAM K. SIMONS.
